Saul Matison
BY David Lichtenstein ATT'y.

UNITED STATES PATENT OFFICE.

NETTIE GREEN, OF CAMBRIDGE, AND SAUL MATISON, OF BOSTON, MASSACHUSETTS.

CHILD'S GARMENT.

1,351,380.

Specification of Letters Patent. Patented Aug. 31, 1920.

Application filed August 12, 1918. Serial No. 249,444.

To all whom it may concern:

Be it known that we, NETTIE GREEN and SAUL MATISON, citizens of the United States of America, and residents, respectively, of Cambridge, in the county of Middlesex and State of Massachusetts, and Boston, in the county of Suffolk and State of Massachusetts, are the joint inventors of a new and useful Improvement in Children's Garments, of which the following is a specification.

The invention relates more particularly to an improvement in children's rompers, which allows for quick and convenient adjustment and disengagement, complete accommodation with avoidance of exposure, and affords a stylish and neat design of garment which is simple and inexpensive to manufacture, and comfortable to wear.

20 The main object of the present invention is the provision of means for ready adjustment in opening or closing the garment and means for normally retaining the garment in closed position.

25 Another object of the invention is the further provision of means for rendering the garment readily and easily applicable to or removable from the body of the wearer.

In order to illustrate the invention we 30 have shown in the accompanying drawing the embodiment thereof, wherein:

Figure 1 represents a front view of the garment.

Fig. 2 represents a rear view thereof.

35 Fig. 3 represents a sectional view taken on line 3—3 in Fig. 2.

Fig. 4 represents a sectional view taken on line 4—4 in Fig. 2.

40 Fig. 5 represents a sectional view taken on line 5—5 in Fig. 2.

The terms employed herein are used in the generic and descriptive sense to indicate elements, and are not therefore specifically or primarily intended as terms of 45 limitation.

In the drawing, 10 in its entirety, designates a body covering better known as "rompers," and comprises the waist and trunk portions 11 and 12, respectively, the former having the neck opening 13, the collar 14 and the sleeves 15, while the latter has the legs 16 which are preferably gathered at 17 over an elastic band, or otherwise, as may be desired.

55 18 represents the front of the garment which is preferably closed throughout, as

shown in Fig. 1. 19 represents the inner rear flap, 20 the outer rear flap, 21 the flap button which is secured to the top of the inner flap 19, 22 the outer flap button-hole 60 which engages with the aforesaid button, 23 the garment crotch, 24 the inner flap extension belt, which is drawn through the open slit 25 provided for the purpose, 26 the outer flap extension belt, 27 and 28 the 65 front plaits, 29 and 30 the rear plaits, and 31 the belt supporting straps formed by the plaits 27, 28 and 29 at the waist band section of the garment where said plaits are preferably disconnected from the garment 70 proper between the stitching 32 and 33, as shown.

The ends of the belts 24 and 26 are preferably brought around to the front of the garment, as shown in Fig. 1, where they are 75 preferably allowed to overlap and are provided with suitable engaging or coupling means, as the button and buttonhole type there shown, or otherwise, as may be desired.

It will now be observed that the rear flaps 19 and 20 extend along the entire length of the garment from the crotch to the neck, and that they overlap each other throughout their lengths, that the widths 85 thereof are made appreciable and therefore afford a positive closing of the opening of the garment when the tops are secured together, as by means of the button and buttonhole 21 and 22, respectively, and when 90 the belt extensions 24 and 26 are coupled together in front of the garment, as shown, then the garment is absolutely relieved of any possibility of the flaps opening up, and the same will remain set and afford a neat 95 appearance to the garment.

To remove the garment from the wearer, it is only necessary to unclasp the neck and belt fastenings, when the garment may be 100 opened in full to allow for the easy removal thereof from the body of the wearer. Similarly the full opening allowed and afforded by the rear flaps, when they are unfastened, permits of a convenient and easily handled garment, especially for children's uses and 105 purposes. The inner flap extension belt 24 is drawn through the open slit 25, provided for the purpose (as shown in Fig. 2) and preferably positioned below the plait 30, and is then drawn through the belt strap 31 110 of the front plait 27, while the outer flap extension belt 26 is drawn through the belt

supporting straps 31 provided therefor in the rear and front plaits 29 and 28, respectively, as shown. The effect thus produced is that of the so-called "Norfolk" style of garment which is a popular design and very pleasing to the eye.

It will be understood that while we have shown the flap joint of the garment positioned in the rear, which is the most preferable, we do not wish to be limited to the use thereof as the same may be used in the front of the garment as well. And also, while we have shown the belt extensions continued to a point where they encircle the body and overlap each other, we do not wish to be limited against employing shorter extensions which may be independently secured to the garment proper, as may well be understood.

While the preferred embodiments of our invention have been described in detail, it will be understood that we do not wish to be limited to the particular construction set forth, since various changes in the form, proportions, and in the details of construction may be resorted to without departing from the spirit and scope of the invention, or destroying any of the advantages contained in the same, heretofore described and defined in the subjoined claims.

Having thus described the invention in detail, what we claim as new is:

1. In a garment having a waist and bifurcated trunk portion, each provided with a tapering flap extending from the crotch to the upper edge of the garment, said flaps being permanently secured in overlapping relation at the crotch and temporarily secured at the upper edge of the garment.

2. In a garment having a waist and a bifurcated trunk portion joined to form a

one-piece garment, an overlapping joint extending from the crotch to the upper end of said garment forming a closure therefor comprising an inner and an outer flap permanently secured in overlapped position at the crotch end of said closure, and means for temporarily securing said overlapping flaps at the uppermost portions thereof for retaining said flaps in closed position while the garment is being worn.

3. In a garment having a waist and a bifurcated portion forming a unit garment, an overlapping joint extending from the crotch to the neck of said garment forming a closure therefor and comprising a tapered inner and a tapered outer flap adapted to overlap each other with the wider portions thereof permanently secured in overlapped position at the crotch of the garment, and the narrower portions thereof positioned at the neck of the garment and adapted to be temporarily secured by co-acting securing means provided on each of said flaps.

4. In a garment having a waist and a bifurcated trunk portion joined to form a one-piece garment, an overlapping joint extending from the crotch to the uppermost portion of said garment forming a closure therefor comprising an inner and an outer flap permanently secured in overlapped position at the crotch end of said closure; means for temporarily securing said overlapping flaps at the uppermost portions thereof; and intermediate strapping means for temporarily securing said flaps in overlapped position.

In testimony whereof we hereunto set our hands this twenty-fifth day of July, 1918.

NETTIE GREEN.
SAUL MATISON.
